ELECTRICAL CONTROLS CABINET

Robert W. Brokaw, Roanoke, Va., assignor to General Electric Company, a corporation of New York

Filed Sept. 21, 1960, Ser. No. 62,218

Term of patent 14 years

(Cl. D26—5)

The FIGURE is a perspective view of the electrical controls cabinet embodying my new design. The right side elevation is similar to the left side elevation, and the rear elevation is substantially plain.

The dominant features of my new design reside in the combination on the cabinet disclosed of the tall narrow vertical panel on one side subtended by the two full-width horizontal panels, the remainder of the front being broken up into several panels of varying height, substantially as shown.

I claim:

The ornamental design for an electrical controls cabinet, as shown and described.
